UNITED STATES PATENT OFFICE.

ADOLPH F. GALL, OF WEST ORANGE, NEW JERSEY, ASSIGNOR, BY MESNE ASSIGNMENTS, TO NEW JERSEY PATENT COMPANY, OF WEST ORANGE, NEW JERSEY, A CORPORATION OF NEW JERSEY.

MOTION-PICTURE-PROJECTING APPARATUS.

1,092,905.

Specification of Letters Patent. Patented Apr. 14, 1914.

Application filed April 20, 1912. Serial No. 691,989.

To all whom it may concern:

Be it known that I, ADOLPH F. GALL, a citizen of the United States, and a resident of West Orange, in the county of Essex and State of New Jersey, have invented certain new and useful Improvements in Motion-Picture-Projecting Apparatus, of which the following is a description.

My invention relates to motion picture projecting apparatus, and especially to the provision of a screen and improved operating means therefor, for protecting the moving picture film from the heat emanating from the projecting lamp.

The principal objects of my invention are to provide for the automatic opening of the screen upon the acquirement by the film driving mechanism of a predetermined speed, to allow the pictures to be properly projected, and the automatic closing of the screen when the speed of the film driving mechanism falls below that predetermined speed; and the provision of improved means for attaining these ends.

Another object of my invention is to provide a construction whereby the screen may be readily applied to that type of projecting apparatus disclosed in my copending application, Serial No. 654,223, filed October 12, 1911.

More particularly described, my invention comprises a screen or shutter located between the projecting lamp and the path of the film and improved means connecting the film operating mechanism and screen for moving the screen as described. The screen is preferably slidably or reciprocably mounted upon the usual film gate, forming a part of motion picture projecting apparatus now in use, and the means for moving said screen preferably comprises a centrifuge adjustably connected to the film operating mechanism, the screen being preferably supported from the centrifuge.

Further objects of my invention will be more fully disclosed in the following description and appended claims:

In order that my invention may be more clearly understood, reference is made to the accompanying drawings, forming a part of this specification, in which the same reference characters designate corresponding parts throughout and in which:

Figure 1 is a side elevation, partly in section, of a portion of a motion picture projecting apparatus, of the type disclosed in my application referred to above, and illustrating one embodiment of my invention as applied thereto; Fig. 2 is a front elevation of the apparatus, shown in Fig. 1, the lower portion being broken away; Fig. 3 is a section on line 3—3 of Fig. 1, the screen being shown in elevation; and Fig. 4 is a sectional view of the apparatus taken on a line through the centrifuge at right angles to its supporting shaft, partly in elevation and partly broken away, and in which the weights of the centrifuge are shown in their outermost positions.

In the accompanying drawings, reference character 1 designates the main support for the film operating mechanism, in which main support an auxiliary support 2 is adjustably mounted. Handle 3, pulley 4, gears 5 and 6, shaft 7 and fly wheel 8 form a part of the film operating mechanism carried by the main and auxiliary supports 1 and 2. To one side of the auxiliary frame 2 is fastened an exposure plate 9 to which is pivoted the film gate 10 by means of a rod 11 mounted in suitable bearings on the exposure plate. The exposure plate has a series of exposure or projection apertures 12 and vertical guide ways 13 for supporting the film. A latch 14 on the exposure plate serves to lock the film gate 10 in closed position, the film gate being provided with an opening 15 registering with projection apertures 12 when the gate is closed, and a tension plate 16 for cooperation with guide ways 13 to hold the film flat while it is fed through exposure position. For a more detailed description of the structure outlined above, reference is made to my copending application above referred to.

In the rear of the film gate is located a film protecting screen 17. This screen is formed of any suitable material, such as aluminum, and is preferably L-shaped, with one leg extending horizontally between the film gate and the exposure plate. The screen is preferably slidably or reciprocably mounted on the film gate 10 in any suitable manner, as by a pair of apertured lugs 18 formed on its vertical leg, loosely engaging rod 11. The lugs 18 preferably extend into notches 19 formed in the exposure plate 9 to limit the movement of the screen. I provide

suitable means whereby, when the film operating mechanism is at rest or is moved slowly, the screen will be supported in a position covering the projection apertures, so as to prevent the film from being injured by the heat from the projecting lamp, but which, when the speed of the operating mechanism attains a predetermined amount, will move the screen to uncover said openings, to allow the pictures to be properly projected. This means preferably comprises an arm 20 pivoted at one end 21 to the auxiliary casing 2 and suitably connected at its other end, as by a yoke 22, to the lower lug 18 of the screen, and a centrifuge 23 co-acting with said arm. The centrifuge preferably comprises a hollow cylindrical casing having one or more weights 24 loosely mounted therein, the outer periphery of the casing being provided with an annular slot 25. The hub 26 of the casing is preferably splined to shaft 7, as by a key 27 and is connected to the auxiliary casing 2 so as to be movable therewith, but free to rotate with respect thereto. Arm 20 is provided with a portion 28 which lies within slot 25 whereby the arm is supported by the uppermost weight 24 of the centrifuge.

The operation is as follows: When the film operating mechanism is at rest, or is driven very slowly, weights 24, arm 20 and screen 17 will be in the positions shown in Figs. 1 and 2 under the action of gravity. Upon the actuation of the film operating mechanism at or above a predetermined speed, however, weights 24 will, under the influence of centrifugal force, assume the positions shown in Fig. 4 forcing arm 20 upwardly and thereby moving screen 17 to uncover openings 12 and 15, to allow the pictures on the film to be properly projected.

Although I have shown a construction in which the screen is applied to a motion picture projecting apparatus of the type disclosed in my application previously referred to, it will be evident that the screen and its operating means may be applied to any motion picture projecting apparatus, such, for example, as one adapted for use only with a film having a single row of pictures. In this case, the splined connection between the centrifuge and its operating shaft would be unnecessary.

Having thus fully described my invention, what I claim and desire to protect by Letters Patent is as follows:

1. In a motion picture projecting apparatus having a projection aperture, film operating mechanism, a screen, a centrifuge having an outwardly movable weight, and a member applied directly to said weight for normally supporting the screen in a position covering said aperture and adapted upon the actuation of said film operating mechanism to be moved by said weight away

from the axis of the centrifuge and thereupon move the screen so as to uncover said aperture, substantially as described.

2. In a motion picture projecting apparatus having a projection aperture, film operating mechanism, a reciprocating screen, and means including a centrifuge comprising a casing having a weight loosely mounted therein operatively connected with the film operating mechanism for normally supporting the screen in a position covering said aperture and adapted upon the actuation of said film operating mechanism to reciprocate the screen so as to uncover said aperture, substantially as described. 70

3. In a motion picture projecting apparatus having a projection aperture, film operating mechanism, a reciprocatory screen normally covering said aperture, and means operatively connected with said film operating mechanism to reciprocate said screen to uncover said aperture upon actuation of the film operating mechanism, said means comprising a centrifuge consisting of a casing with a plurality of weights loosely mounted therein, substantially as described. 85

4. In a motion picture projecting apparatus having a projection aperture, film operating mechanism, means operatively connected with said film operating mechanism comprising a centrifuge having a movable weight, a screen, and means applied directly to said weight and normally supporting the screen in a position covering said aperture, the actuation of the said mechanism causing the weight to actuate said last named means and thereby move the screen to uncover said aperture, substantially as described. 95

5. In a motion picture projecting apparatus having a projection aperture, film operating mechanism, a screen, and means connecting the screen and film operating mechanism comprising a centrifuge having a movable weight and a screen-operating member applied directly to said weight and normally supporting said screen in a position covering said aperture, the actuation of the film operating mechanism causing the weight to actuate said member and thereby move said screen to uncover said aperture, substantially as described. 105

6. In a motion picture projecting apparatus having a projection aperture, film operating mechanism, a screen, means operatively connected to the film operating mechanism for controlling the position of said screen comprising a rotatable cylindrical casing containing a plurality of weights movable outwardly under centrifugal action, said casing having an annular slot in its outer periphery, and an arm pivoted at one end and connected to the screen at its other end, said arm lying in said slot for engagement with the weights, substantially as described. 110

7. In a motion picture projecting apparatus, the combination with the main support carrying film operating mechanism and the auxiliary support having a plurality of projection apertures and adjustable in the main support so that any one of its apertures may be brought in the path of the projecting light, of a screen normally covering the aperture in the path of the light, and means movable with the auxiliary support and operatively connected with the film operating mechanism adapted upon actuation of said film operating mechanism to move said screen to uncover said last named aperture, substantially as described.

8. In a motion picture projecting apparatus, the combination with the main support carrying film operating mechanism and the auxiliary support having a plurality of projection apertures and adjustable laterally in the main support so that any one of its apertures may be brought in the path of the projecting light, of a screen, and means for normally supporting said screen in a position covering said apertures, said means being movable with said auxiliary support and operatively connected with the film operating mechanism and adapted upon actuation of the film operating mechanism to move the screen to uncover said apertures, substantially as described.

9. In a motion picture projecting apparatus, the combination with the main support carrying film operating mechanism, the auxiliary support having a plurality of projecting apertures and adjustable in the main support so that any one of its apertures may be brought in the path of the projecting light and the film gate on the auxiliary support having an aperture registering with the apertures of the auxiliary support when the gate is closed, of a screen on said gate, and means movable with the auxiliary support for normally supporting the screen in a position covering said apertures and adapted on actuation of the film operating mechanism to move the screen to uncover the apertures, said means including a centrifuge comprising a hollow casing and a weight mounted therein, substantially as described.

10. In a motion picture projecting apparatus, the combination with the main support carrying film operating mechanism and the auxiliary support having a plurality of projection apertures and adjustable in the main support so that any one of its apertures may be brought in the path of the projecting light, of a screen, and means movable with the auxiliary support for normally supporting the screen in a position covering said apertures, and adapted on actuation of the film operating mechanism to move the screen to uncover said apertures, said means including a centrifuge comprising

ing a slotted casing with a weight mounted therein and a pivoted arm connected to the screen and lying within the slot of the said casing in contact with said weight, substantially as described.

11. In a motion picture projecting apparatus, the combination with the main support carrying film operating mechanism and the auxiliary support having a plurality of projection apertures and adjustable in the main support so that any one of its apertures may be brought in the path of the projecting light, of a screen normally covering the aperture in the path of the light, and means movable with the auxiliary support adapted upon actuation of said film operating mechanism to move said screen to uncover said last named aperture, said means including a centrifuge comprising a casing having a weight mounted therein, substantially as described.

12. In a motion picture projecting apparatus having a projection aperture, film operating mechanism, a reciprocating screen normally covering said aperture, and means operatively connected with said film operating mechanism to reciprocate said screen to uncover said aperture upon actuation of the film operating mechanism, said means comprising a casing having a weight loosely mounted therein, substantially as described.

13. In a motion picture projecting apparatus, a movably mounted screen, a screen-operating member, and a centrifuge comprising an outwardly movable weight, said weight being applied directly to said screen-operating member and causing, by its outward movement, movement of the screen-operating member away from the axis of the centrifuge, substantially as described.

14. In a motion picture projecting apparatus, a movably mounted screen, a pivoted screen-operating member and a centrifuge comprising an outwardly movable weight, said weight being applied directly to said screen-operating member and causing, by its outward movement, movement of the screen-operating member about its pivot and away from the axis of the centrifuge, substantially as described.

15. In a motion picture projecting apparatus, a movably mounted screen, a pivoted screen-operating member connected directly to said screen and a centrifuge comprising an outwardly movable weight, said weight being applied directly to said screen-operating member and causing, by its outward movement, movement of the screen-operating member about its pivot and away from the axis of the centrifuge, substantially as described.

16. In a motion picture projecting apparatus, a movably mounted screen, a centrifuge comprising a casing and an outwardly movable weight therein, means for

actuating said centrifuge, and screen-operating means separate from said centrifuge and actuating means and comprising a member applied directly to said weight and 5 actuated by the outward movement thereof, substantially as described.

17. In a motion picture projecting apparatus, a movably mounted screen, a centrifuge comprising a casing and an outwardly movable weight therein, means for actuating said centrifuge, and a pivoted screen-operating member directly connected with said screen and applied directly to said weight, said weight causing, by its outward movement, movement of said member about its pivot, substantially as described.

18. In a motion picture projecting apparatus, a main support carrying film operating mechanism, an auxiliary support carrying the film and laterally adjustable on said main support, a movably mounted screen in the rear of the film, and screen-operating means movable with the auxiliary support and driven by the film operating mechanism 20 of the main support, substantially as described.

19. In a motion picture projecting apparatus, a main support carrying film operating mechanism, an auxiliary support carry-

ing the film and laterally adjustable on said main support, a movably mounted screen in the rear of the film, and screen-operating means movable with the auxiliary support and driven by the film operating mechanism of the main support, said means comprising a centrifuge having an outwardly movable weight and a member connected with said screen and applied directly to said weight, the outward movement of said weight causing movement of said member away from the axis of the centrifuge, substantially as described.

20. In a motion picture projecting apparatus, a main support carrying film operating mechanism, an auxiliary support carrying the film and laterally adjustable on the main support, a movably mounted screen in the rear of the film, and screen-operating means movable with the auxiliary support and driven by the film operating mechanism of the main support, said means comprising a centrifuge, substantially as described.

This specification signed and witnessed this 19th day of April 1912.
